(57) **CLAIM**

The ornamental design for push button pill reminder with register, as shown and described.

DESCRIPTION

FIG. 1 is a perspective view of a first embodiment of a push button pill reminder with register, according to our design;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof;

FIG. 8 is a perspective view of a second embodiment of a push button pill reminder with register, according to our new design, the portions shown in broken lines forming no part of the design sought to be patented;

FIG. 9 is a front view thereof;

FIG. 10 is a rear view thereof;

FIG. 11 is a right view thereof;

FIG. 12 is a left view thereof;

FIG. 13 is a top view thereof, the portions shown in broken lines forming no part of the design sought to be patented;

FIG. 14 is a bottom view thereof, the portions shown in broken lines forming no part of the design sought to be patented;

FIG. 15 is a perspective view of a third embodiment of a push button pill reminder with register, according to our new design, the portions shown in broken lines forming no part of the design sought to be patented;

FIG. 16 is a front view thereof;

FIG. 17 is a rear view thereof;

FIG. 18 is a right view thereof;

FIG. 19 is a left view thereof;

FIG. 20 is a top view thereof, the portions shown in broken lines forming no part of the design sought to be patented;

FIG. 21 is a bottom view thereof, the portions shown in broken lines forming no part of the design sought to be patented;

FIG. 22 is a perspective view of a fourth embodiment of a push button pill reminder with register, according to our design;

FIG. 23 is a front view thereof;

FIG. 24 is a rear view thereof;

FIG. 25 is a right view thereof;

FIG. 26 is a left view thereof;

FIG. 27 is a top view thereof;

FIG. 28 is a bottom view thereof;

FIG. 29 is a perspective view of a fifth embodiment of a push button pill reminder with register, according to our new design, the portions shown in broken lines forming no part of the design sought to be patented;

FIG. 30 is a front view thereof;

FIG. 31 is a rear view thereof;

FIG. 32 is a right view thereof;

FIG. 33 is a left view thereof;

FIG. 34 is a top view thereof, the portions shown in broken lines forming no part of the design sought to be patented; and,

FIG. 35 is a bottom view thereof, the portions shown in broken lines forming no part of the design sought to be patented.
